UNITED STATES PATENT OFFICE.

HOWARD J. MURPHY, OF READING, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

LUBRICATING APPARATUS.

Application filed February 11, 1925. Serial No. 8,582.

This invention aims to provide an improved pressure lubricating system.

In the drawings, which illustrate a preferred form of my invention:

5 Figure 1 is a central longitudinal section of a lubricant-expelling gun, being partly in elevation;

10 Fig. 2 is an enlarged central longitudinal section of the nozzle shown in Fig. 1, with the lubricant-receiving part partly engaged in the nozzle, some of the parts being in elevation; and

15 Fig. 3 is a section similar to Fig. 2, but with the lubricant-receiving part fully entered within the nozzle and the valve fully opened.

20 Referring to the drawings, I have shown a lubricant-expelling device which is simple, compact and inexpensive in construction, and which also includes means for expelling lubricant under a relatively low potential pressure, a relatively high potential or an initial high pressure and then a low pressure, all of which may be accomplished by very simple operations. With the device illustrated, lubricant may be expelled under relatively higher potential pressure with a lesser amount of torque than has heretofore been possible in other known devices for similar use.

25 30 The drawings show a lubricant-expelling gun including a barrel 1 having a rear head 2 into which is threaded a plunger stem 3 carrying the usual plunger 4 interiorly of the barrel 1, and a handle 5. At the discharge end of the gun, I have shown a front head 6, which is formed as a part of the barrel 1 and tapers from the barrel of the gun to a forwardly projecting portion 7 interiorly threaded to engage the exterior 35 threads of a nozzle part hereinafter more fully described.

40 45 A coupling member 9 is threadedly secured to the intermediate part 8 and presents interiorly thereof relatively steep pitch threads, herein shown as triple, for engagement with the threads on the lubricant-receiving part or nipple 9^a, as illustrated in Figs. 2 and 3.

50 The coupling member 9 is also provided with a steel washer 10 and a sealing or hat washer 11, which are held in place between the end of the aligning part 8 and a shoulder in the coupling 9 thereby to provide sealing

means to prevent leakage of lubricant past the periphery of the lubricant-receiving nipple 9^a (Fig. 3). Thus the lubricant-receiving nipple, coupling and sealing means are substantially as shown and more fully described in my co-pending application Serial No. 616,802.

55 60 The nozzle 6 of the lubricant-expelling device is provided with a lubricant-receiving chamber 12 having means at each end thereof for entrapping the lubricant in the chamber. At the discharge end of the chamber 12, I have provided an inwardly opening closure valve 13 which is normally held seated against the valve seat 15 by suitable spring means herein shown as a spring 16. At the inner end of the chamber 12, I have provided a valve-carrying part 17, which carries an outwardly opening check valve 18 normally urged into closed position by suitable spring means herein shown as a spring 19 interposed between the check valve and a collar 20. 65 70 The collar 20 is driven into the open end of the valve-carrying part 17 and provides a seat for one end of the spring 16 and one end of the spring 19.

75 80 Engagement of the lubricant-expelling gun with the lubricant-receiving nipple 9^a may be effected by introducing the coupling over the smooth end 21 of the lubricant-receiving nipple and turning the barrel 1 of the gun in a clockwise direction, this being 85 the direction which the threaded stem 3 is turned to effect expulsion of lubricant from the barrel 1. Thus the coupling member 9, which is rigidly secured to the barrel 1, is rotated in a clockwise direction and the 90 female threads located in the coupling engage the male threads on the lubricant-receiving nipple, thereby drawing the coupling member 9 over the lubricant-receiving nipple. During coupling engagement of the 95 lubricant-expelling gun with the lubricant-receiving nipple, the smooth end 21 of the nipple passes through an aperture in the washer 10 and the hat washer 11 and forces inwardly the closure valve 13, as best illustrated in Figs. 2 and 3.

100 105 The steel washer 10 provides a new and useful function in this device because it not only centers the nozzle relative to the nipple but also acts as a stop against which the male threads of the nipple may abut during

coupling action, thereby to limit the movement of the nozzle over the nipple, as best illustrated in Fig. 3.

Rotation of the handle 5 in a clockwise direction after the lubricant-expelling gun has been coupled with the lubricant-receiving nipple, forces the piston 4 inwardly relative to the barrel 1, thereby forcing lubricant under relatively low pressure from the barrel 10 past the ball check 18 through the chamber 12, and then past the closure valve 13 and through the slot 22 in the front end of the closure valve into the lubricant-receiving nipple 9^a. Lubricant forced into the lubricant-receiving nipple in the above-mentioned manner is under a relatively low potential pressure which is sufficient to lubricate a bearing free from dirt or hardened lubricant. The low potential pressure will depend on the diameter of the barrel, the pitch of the threads on the stem 3 and the torque applied thereto. As compared with the high potential pressure hereinafter described, pressures of even one or two thousand 25 pounds per square inch may be considered low.

If a bearing cannot be properly lubricated with lubricant that is forced to it under a relatively low potential pressure, the pressure of the lubricant may be greatly increased by permitting the barrel 1 to be turned in a contra-clockwise direction so that the closure valve 13 may return to its seat and allow the chamber 12 to become 30 filled with lubricant. The chamber 12, as the valve 13 closes, becomes filled with lubricant because the pressure on the lubricant in the barrel forces some of the lubricant past the ball check 18 and into the chamber 12.

40 By turning the handle 5 again in a clockwise direction, the closure valve 13 is forced open and into the chamber 12 by the smooth end of the lubricant-receiving nipple 9^a, which acts as a displacing plunger to force lubricant from the chamber 12 at a relatively 45 high potential pressure. When forcing lubricant under high pressure, the torque exerted upon the handle 5 does not have to be as great as when forcing lubricant under low pressure. While the lubricant is being thus forced from the chamber 12, it is prevented from leaking back into the barrel 1 by the ball check 18 which traps the lubricant in the chamber 12.

55 The torque to produce high pressure may be exerted on the barrel 1 instead of on the handle 5.

Removal of the gun from the lubricant-receiving nipple is effected by turning the 60 handle 5 in a contra-clockwise direction to unscrew the coupling threads from the threads on the lubricant-receiving nipple, thereby permitting the closure valve 13 to be closed by the spring 16, disengagement 65 being effected by sliding the coupling of

the gun over the smooth end 21 of the nipple 9^a substantially as described in the above-mentioned application.

Even aside from its broader aspects, the construction illustrated involves many important features. Thus the inwardly opening valve 13 prevents leakage of lubricant when the nozzle is disconnected from the nipple, notwithstanding that very substantial pressure may be left in the barrel 1, 70 and the location of this valve in front of the compression chamber instead of behind it entraps lubricant so that it will not run out when disengaged even though very fluid. Additionally, in ordinary operation the 75 chamber 12 will be full each time that the nozzle is disconnected from a nipple so that during the coupling operation the next nipple is automatically subjected to a very high potential pressure, say 12,000 pounds 80 or more. Of course the actual pressure exerted will depend upon the resistance opposed to expulsion of the lubricant from the chamber 12, and when the bearing to be lubricated is free, very little of the potential 85 pressure may be utilized, the coupling operation requiring correspondingly less torque. 90

While I have shown and described a preferred form of one embodiment of my invention, it will be understood that changes 95 involving omission, alteration, substitution and reversal of parts, and even changes in the mode of operation, may be made without departing from the scope of my invention, which is best defined in the following 100 claims.

I claim:

1. Lubricant apparatus for injecting grease or oil into machine bearings comprising, in combination, a source of lubricant under pressure above atmospheric, means forming a chamber in lubricant communication with said source and a coupling for connection to a lubricant receiving nipple, said coupling having a movable connection with said nipple permitting the latter alternately to expand and contract the effective volumetric lubricant receiving capacity of said chamber, sealing means engaging the periphery of said nipple for rendering fluid tight the joint between said coupling and nipple, and valvular means controlling lubricant flow from said source into said chamber effective to permit flow only from said source to said chamber and to prevent return flow. 110

120 2. Lubricant apparatus for injecting grease or oil into machine bearings through lubricant receiving nipples associated with said bearings comprising, in combination, a lubricant reservoir provided with a lubricant exit and lubricant displacing means for forcing lubricant from said reservoir through said exit, lubricant conducting conduit means receiving the lubricant from said exit, said conduit means formed to receive said 125 130

- nipples, cooperating cam means on said nipples and said conduit means for causing relative rotation of said conduit means and nipples to effect relative reciprocation of the 5 two for alternately expanding and contracting the volumetric lubricant receiving capacity of said conduit means, and valvular means for closing communication between said conduit means and reservoir when the 10 capacity of said conduit means is being contracted and for establishing such communication when the capacity is being expanded, valve means adjacent the discharge end of said conduit means for positively preventing 15 egress of lubricant when the nipple is removed therefrom, and sealing means for rendering lubricant tight the joint between said nipple and nozzle when said nipple is entered into said conduit means and said valve 20 means is opened to permit discharge from said conduit means.
3. Apparatus for injecting oil or grease into machine bearings comprising, in combination, means providing a source of lubricant under pressure, lubricant conducting conduit means connected to said source comprising a discharge nozzle adapted to receive a lubricant receiving nipple, said conduit means having a check valve and normally closed valve means beyond said check valve, said check valve operative to permit flow of lubricant from said source toward said nozzle and to oppose return flow, and said normally closed valve means adapted to 35 be positively opened when the nipple is entered into said nozzle.
4. Apparatus for injecting oil or grease into machine bearings comprising, in combination, means providing a source of lubricant under pressure, lubricant conducting conduit means connected to said source comprising a discharge nozzle adapted to receive a lubricant receiving nipple, said conduit means having a check valve and normally closed valve means beyond said check valve, said check valve operative to permit flow of lubricant from said source toward said nozzle and to oppose return flow, said normally closed valve means in said nozzle 45 adapted to be mechanically opened when the nipple is entered into said nozzle, and sealing means for rendering fluid tight the joint between said nozzle and nipple.
5. Apparatus for injecting oil or grease into machine bearings comprising, in combination, means providing a source of lubricant under pressure, lubricant conducting conduit means connected to said source comprising a discharge nozzle adapted to receive 55 a lubricant receiving nipple, said conduit means having a check valve and normally closed valve means beyond said check valve, said check valve operative to permit flow of lubricant from said source toward said nozzle and to oppose return flow, said normally 60 closed valve and to oppose return flow, said normally closed valve means adapted to be opened solely by the entrance of the nipple into said nozzle, and cam means presented partly by said nipple and partly by said nozzle for drawing one toward the other by relative 70 rotation for compressing the lubricant in advance of the check valve during opening movement of said normally closed valve.
6. Lubricant apparatus for injecting oil or grease or oil under pressure into machine bearings comprising, in combination, means forming a chamber, a source of lubricant under pressure above atmospheric, said source connected to said chamber through valve means permitting passage of lubricant from said 75 source to said chamber and preventing return flow, a lubricant receiving nipple, a coupling for connecting said chamber to said nipple providing for relative movement between said nipple and coupling for forcing 80 lubricant from said chamber into said nipple, a closure valve in said coupling adapted to be opened when said coupling is connected to said nipple, and a check valve in said nipple acting to prevent escape of lubricant 85 therefrom.
7. Lubricant apparatus for injecting oil or grease or oil under pressure into machine bearings comprising, in combination, means forming a chamber, a source of lubricant under pressure above atmospheric, said source connected to said chamber through valve means permitting passage of lubricant from said source to said chamber and preventing 90 return flow, a lubricant receiving nipple, a coupling for connecting said chamber to said nipple providing for relative movement between said nipple and coupling for forcing 95 lubricant from said chamber into said nipple, inwardly opening valve means at one end of said chamber adapted to be opened when the lubricant receiving nipple is entered into said coupling, sealing means providing a lubricant tight seal between said coupling and said nipple, and a check valve 100 in said nipple acting to prevent escape of lubricant therefrom.
8. Lubricant apparatus for injecting oil or grease or oil under pressure into machine bearings comprising, in combination, means forming a chamber, a source of lubricant under pressure above atmospheric, said source connected to said chamber through valve means permitting passage of lubricant from said source to said chamber and preventing 105 return flow, a lubricant receiving nipple, a coupling for connecting said chamber to said nipple providing for relative movement between said nipple and coupling for forcing lubricant from said chamber into said nipple, and sealing means carried by said coupling for engagement with the periphery of said nipple to provide a lubricant tight seal 110 between said coupling and said nipple.
9. Lubricating apparatus comprising, in 115
- 120
- 125
- 130

combination, a barrel, means for expelling lubricant from said barrel, means forming a chamber generally aligned with said barrel and presenting a substantially smaller cross-sectional area than said barrel, a valve controlling communication between said barrel and said chamber to permit passage of lubricant in one direction only, a coupling beyond said chamber for engagement with a lubricant-receiving nipple, and valve means at one end of said chamber actuated by relative movement between said coupling and said lubricant-receiving nipple to permit said nipple to discharge lubricant from said chamber under relatively high potential pressure.

20. Lubricating apparatus comprising, in combination, a barrel, means for expelling lubricant from said barrel, means forming a chamber generally aligned with said barrel and presenting a substantially smaller cross-sectional area than said barrel, a valve between said barrel and said chamber to permit passage of lubricant in one direction, 25 only, a coupling beyond said chamber for engagement with a lubricant-receiving nipple, and a valve adjacent the outer end of said chamber and normally closing said end, said valve adapted to engage said lubricant 30 receiving nipple when said chamber is moved toward said lubricant-receiving nipple thereby unseating said valve and permitting said nipple to force lubricant out of said chamber into said lubricant-receiving nipple under a relatively high potential pressure. 35

11. Lubricating apparatus comprising, in combination, a barrel, means for expelling lubricant from said barrel under a relatively low potential pressure, a handle for manually operating said means, a chamber of substantially smaller cross-sectional area than said barrel located in a fixed relation to said barrel, means permitting flow of lubricant from said barrel to said chamber and preventing reverse flow, and a coupling for said chamber for movable engagement with a lubricant-receiving part, said handle operative to expel lubricant under high or low potential pressure into said lubricant-receiving part.

12. Lubricating apparatus comprising, in combination, a barrel, manually operable means for expelling lubricant therefrom, a chamber located in a fixed relation relative to said barrel and having a cross-sectional area substantially less than said barrel, a check valve located at the inner end of said chamber to permit passage of lubricant only from said barrel to said chamber, a coupling for said chamber for engagement with a lubricant-receiving part, and means operative in one direction to permit passage of lubricant from said barrel by way of said chamber to said lubricant-receiving part under a

relatively low potential pressure and operative in the opposite direction to prevent lubricant flow from said chamber for permitting filling of said chamber with lubricant from said barrel and thereafter operative in the first-mentioned direction to permit said part to force the lubricant, entrapped in said chamber by said check valve, into said lubricant-receiving part under relatively high potential pressure. 65
70

13. Lubricating apparatus comprising, in combination, a barrel, manually-operable expelling means for forcing lubricant therefrom, a valve-carrying part secured to said barrel, a chamber in said valve-carrying part presenting a substantially smaller cross-sectional area than said barrel, a coupling secured to said valve-carrying part, for engagement with a lubricant-receiving part, and a valve at the inner end of said chamber to permit passage of lubricant from said barrel into said chamber and to prevent return flow, said lubricant thereafter forced from said chamber by relative movement between said coupling and said lubricant-receiving part. 75 80 85 90 95

14. A pressure device for lubricating apparatus comprising, in combination, a lubricant-receiving chamber having a relatively small cross-sectional area, a coupling beyond said chamber for engagement with a lubricant-receiving nipple, means for entrapping lubricant in said chamber, a lubricant-pressed hat washer adapted to fit over the end of said lubricant-receiving nipple and a spring-pressed valve normally closing the outlet end of said chamber, said valve actuated by movement of said chamber toward said lubricant-receiving nipple to permit lubricant to be forced from said chamber into said lubricant-receiving part under a relatively high potential pressure. 95 100 105

15. A pressure device for lubricating apparatus comprising, in combination, a lubricant-receiving chamber having a relatively small cross-sectional area, a coupling for said chamber for engagement with a lubricant-receiving nipple, sealing means fixed relative to said coupling for preventing leakage of lubricant from said chamber past said lubricant-receiving nipple, a spring-pressed check valve located at the inlet end of said chamber to trap the lubricant in said chamber after it has passed said check valve, and a closure valve located at the front end of said chamber and operated by engagement thereof with the end of said nipple to permit displacement of lubricant from said chamber under relatively high potential pressure by said nipple.

16. Lubricating apparatus comprising, in combination, a barrel, means for expelling lubricant therefrom, a chamber having a substantially smaller cross-sectional area

than said barrel, means for entrapping lubricant in said chamber, a coupling presenting a plurality of female threads, a lubricant-receiving part presenting cooperating 5 male threads, and a valve engageable with the end of said lubricant-receiving part and opened thereby to permit passage of lubricant from said barrel through said chamber under a relatively low potential pressure to 10 said lubricant-receiving part when said coupling is rotated to engage the female threads with the male threads of said lubricant-receiving part.

17. A pressure booster for lubricating apparatus comprising, in combination, means forming a chamber adapted to receive lubricant, valves at both ends of said chamber to trap lubricant therein, a coupling beyond said chamber presenting a plurality of female 20 threads, and a lubricant-receiving part presenting a plurality of male threads for engagement with said female threads, the pitch of said threads being such that said coupling may be rotated by the pressure of 25 lubricant in said chamber when said coupling is engaged with said lubricant-receiving part.

18. Lubricating apparatus comprising, in combination, a barrel, manually operable 30 means for expelling lubricant from said barrel under relatively low potential pressure, means forming a chamber rigidly secured to said barrel, a coupling for said chamber rigidly secured thereto for engagement 35 with a lubricant-receiving nipple, a ball check between said barrel and said chamber for trapping the lubricant in said chamber, and a closure valve at the outlet end of said chamber operable by said nipple 40 to permit entrance of said nipple into said chamber whereby to force lubricant from said chamber into said nipple under a relatively high potential pressure.

19. Lubricating apparatus comprising, in combination, a container for supplying lubricant under a relatively low potential pressure, a lubricant-receiving nipple presenting the male portion of a coupling, a discharge nozzle, lubricant-conducting conduit means 45 connecting said container with said nozzle, said nozzle having a female portion for coupling engagement with said nipple, said nozzle and nipple presenting cooperating inclined means for drawing said nozzle over 50 said nipple when said nozzle is turned relative to said nipple, said nozzle containing an inwardly opening closure valve openable by said nipple when said nozzle is connected to said nipple, and a check valve in said conduit means between said closure valve and said container, said check valve permitting flow of lubricant from said container but opposing reverse flow of the lubricant.

20. Lubricating apparatus comprising, in combination, a container for supplying lu-

bricant under a relatively low potential pressure, a lubricant-receiving nipple presenting the male portion of a coupling, a discharge nozzle, lubricant-conducting conduit means connecting said container with said nozzle, 70 said nozzle having a female portion for coupling engagement with said nipple, said nozzle and nipple presenting cooperating inclined means for drawing said nozzle over said nipple when said nozzle is turned relative to said nipple, said nozzle containing an inwardly opening closure valve openable by said nipple when said nozzle is connected to said nipple, a check valve in said conduit means between said closure valve and said container, said check valve permitting flow of lubricant from said container but opposing reverse flow of the lubricant, and a peripheral lubricant-pressed seal in said nozzle seated against the periphery of said nipple 85 during the entire opening and closing of said closure valve.

21. Lubricating apparatus comprising, in combination, a container for supplying lubricant under a relatively low potential 90 pressure, a lubricant-receiving nipple presenting the male portion of a coupling, a discharge nozzle, lubricant-conducting conduit means connecting said container with said nozzle, said nozzle having a female portion 95 for coupling engagement with said nipple, said nozzle and nipple presenting cooperating inclined means for drawing said nozzle over said nipple when said nozzle is turned relative to said nipple, said nozzle containing an inwardly opening closure valve openable by said nipple when said nozzle is connected to said nipple, an annular seat for said closure valve adapted to surround said nipple when the latter is fully entered 100 into said nozzle, and a check valve in said conduit means between said closure valve and said container, said check valve permitting flow of lubricant from said container but opposing reverse flow of the lubricant: 110

22. Lubricating apparatus comprising, in combination, a container for supplying lubricant under a relatively low potential pressure, a lubricant-receiving nipple presenting the male portion of a coupling, a discharge nozzle, lubricant-conducting conduit means connecting said container with said nozzle, said nozzle having a female portion for coupling engagement with said nipple, said nozzle and nipple presenting cooperating inclined means for drawing said nozzle over said nipple when said nozzle is turned relative to said nipple, said nozzle containing an inwardly opening closure valve openable by said nipple when said nozzle is connected to said nipple, an annular seat for said closure valve having an internal diameter greater than the end portion of said nipple, and a check valve in said conduit means between said closure valve and said 120

130

container, said check valve permitting flow of lubricant from said container but opposing reverse flow of the lubricant.

23. A lubricant-expelling device comprising, in combination, a barrel, a reduced end portion integral with one end of said barrel, a valve-carrying part adapted to fit said reduced portion and carrying a check valve adjacent one end thereof and a closure valve adjacent the other end, said part having a high pressure chamber between said valves of a cross-sectional area substantially smaller than said barrel, coupling means carried by said part for engagement with a lubricant-receiving nipple, and a hat washer in said part forwardly of said closure valve for engagement with said nipple.

24. A lubricant-expelling device comprising, in combination, a barrel, a plunger in said barrel, a threaded stem for said plunger, an operating handle on said stem, a nut for said stem carried by one end of said barrel, a reduced end portion integral with the end of said barrel opposite said nut, a valve-carrying part adapted to fit said reduced portion and carrying a check valve adjacent one end thereof and a closure valve adjacent the other end, said part having a high pressure chamber between said valves of a cross-sectional area substantially smaller than said barrel, coupling means carried by said part for engagement with a lubricant-receiving nipple, and a hat washer in said part forwardly of said closure valve for engagement with said nipple.

25. Lubricating apparatus for forcing grease or oil under pressure into machine bearings through nipples associated with said bearings having, in combination; means forming a lubricant receiving chamber and a nozzle for connection to a nipple, a receptacle for the lubricant supply for said chamber; a lubricant displacing member in said receptacle, a screw threaded stem for actuating said displacing member, means forming a nut carried by said receptacle for coaction with said stem, a handle for said stem; and means including cooperating cam means on said nozzle and nipple and lubricant conducting passages for effecting by rotation of said handle connection of said nozzle to said nipple and thereafter forcing lubricant under relatively low potential pressure from said receptacle into said chamber and from said chamber under relatively high potential pressure into said nipple, said means including a lubricant actuated valve device for interrupting communication between said receptacle and chamber.

26. Lubricating apparatus for forcing grease or oil under pressure into machine bearings through nipples associated with said bearings having, in combination; means forming a relatively non-rotatable lubricant receiving chamber, nozzle for connection to a

nipple, and lubricant receptacle; an operating handle connected to a stem extending into said receptacle, a lubricant displacing member in said receptacle operatively connected to said stem; and means actuated by rotation of said handle for connecting said nozzle to a nipple and thereafter forcing lubricant under relatively low potential pressure by said displacing member from said receptacle into said chamber and forcing the lubricant under relatively high potential pressure from said chamber into said nipple, said means comprising a fluid actuated valve device for interrupting communication between said receptacle and chamber. 70 75 80

27. Lubricating apparatus for forcing grease or oil under pressure into machine bearings through nipples associated with said bearings having, in combination, means forming a lubricant receptacle and communicating lubricant receiving chamber and nozzle for connection to a nipple, a normally closed valve device for controlling communication between said chamber and nozzle, an operating handle, and means actuated by rotation of said handle to effect forcing of lubricant under relatively low potential pressure from said receptacle into said chamber and from said chamber under relatively high potential pressure past said valve into a 95 nipple, said means comprising a lubricant actuated valve device for interrupting communication between said receptacle and chamber. 90 95 100

28. Lubricating apparatus for forcing 100 grease or oil under pressure into machine bearings through nipples associated with said bearings having, in combination; means forming a relatively non-rotatable lubricant receiving chamber, nozzle for connection to a nipple, and lubricant receptacle, said nozzle having means for sealing the joint between the same and said nipple; an operating handle connected to a stem extending into said receptacle, a lubricant displacing member in said receptacle operatively connected to said stem; and means actuated by rotation of said handle for connecting said nozzle to a nipple and thereafter forcing lubricant under relatively low potential pressure by said displacing member from said receptacle into said chamber and forcing the lubricant under relatively high potential pressure from said chamber into said nipple, said means comprising a fluid actuated valve device for interrupting communication between said receptacle and chamber. 105 110 115 120 125

29. Lubricating apparatus for forcing grease or oil under pressure into machine bearings through nipples associated with said bearings having, in combination; means forming a relatively non-rotatable lubricant receiving chamber, nozzle for connection to a nipple, and lubricant receptacle, said nozzle having sealing means for engaging the 130

periphery of said nipple; an operating handle connected to a stem extending into said receptacle, a lubricant displacing member in said receptacle operatively connected to said stem; and means actuated by rotation of said handle for connecting said nozzle to a nipple and thereafter forcing lubricant under relatively low potential pressure by said displacing member from said receptacle into said chamber and forcing the lubricant 10 under relatively high potential pressure from said chamber into said nipple, said means comprising a fluid actuated valve device for interrupting communication between said receptacle and chamber. 15

In testimony whereof, I have signed my name to this specification.

HOWARD J. MURPHY.
